CAR DOOR

Frank Ditchfield, Cleveland, Ohio, assignor to
The Youngstown Steel Door Company, Cleve-
land, Ohio, a corporation of Ohio

Application September 7, 1938, Serial No. 228,780

7 Claims. (Cl. 16—99)

This invention relates to car doors and more particularly to sliding doors of the lift type for railway house cars.

To prevent or materially decrease sliding movement of car doors during shunting, switching, etc., of railway freight cars, the doors are frictionally supported in lowered position upon tracks. To secure desired movement of the doors along the tracks with a minimum of effort they are elevated above the tracks and disposed upon rolling means. Elevation is accomplished by mechanism denoted as lift mechanism usually carried by the doors. Operation of the lift mechanism is accomplished by means of a lever.

It has been found that the stresses and movement of freight cars equipped with sliding lift doors cause a whipping or chattering action of the levers which in time produces wear in the levers and related parts of the mechanisms. As such wear progresses the levers gradually depart from their initial positions and in so doing reduce the amount of lift obtainable.

It is, therefore, the main object of this invention to provide simple, inexpensive and effective means capable of eliminating or substantially reducing the whipping or chattering action of the levers of lift mechanisms.

A further object is to provide means capable of maintaining the levers substantially in their initial positions and thereby prevent reduction in the amount of lift obtainable.

It is a further object to provide resilient means capable of preventing whipping or chattering action of the actuating levers of lift mechanisms.

Other objects of the invention will become clear as the description thereof proceeds.

In the drawings forming part of this specification:

Figure 1 is a partial elevation of a sliding lift door embodying one form of the invention, parts being broken away.

Figure 2 is an enlarged elevational detail of a portion of the lift mechanism, the door being shown in lowered position and a portion being broken away for the sake of clarity.

Figure 3 is a view similar to Figure 2, the door being shown in elevated position.

Figure 4 is a sectional view taken on line 4—4 of Figure 3.

Figure 5 is a sectional view taken on line 5—5 of Figure 3.

Figure 6 is a partial elevation showing a modified form of the invention.

Figure 7 is an enlarged detail of a portion of the door of Figure 6, a part being broken away

for greater clarity and the door being shown in lowered position.

Figure 8 is a view similar to Figure 7, the door being shown in elevated position.

Figure 9 is a vertical section taken on line 9—9 of Figure 7.

In the embodiment of the invention illustrated in Figures 1 to 5 inclusive of the drawings the numeral 10 designates a metallic door selected for the purpose of illustrating the invention. The door 10 embodies a metallic panel 11 formed with horizontal corrugations 12 and marginal vertical corrugations 13 and 14. Reinforcing backing plates 15 and 16 extend across the vertical corrugations 13 and 14 and are secured to the metallic panel on opposite sides thereof as best illustrated in Figure 1 of the drawings. The vertical margins of the metallic panel 11 are additionally reinforced by means of a channel shaped member 17 secured to the front vertical margin and by means of an angle member 18 secured to the rear vertical margin.

The lower marginal portion of the metallic panel 11 is reinforced by means of a backing plate 19 which extends across the lowermost horizontal corrugation 12 and is secured to the panel on opposite sides thereof as clearly appears from Figure 1 of the drawings. Additional reinforcement is provided by means of an angle member 20, the vertical leg 21 of which is disposed between the backing plate 19 and the lower margin of the panel 11 and is secured thereto. The horizontal leg 22 of the reinforcing angle member projects outwardly from the panel as best shown in Figures 1 and 5 of the drawings and provides means whereby the door is frictionally supported in its lowered position upon a track 23. This track is secured to a side sill 24 by means of a plurality of brackets 25—25.

In order to move the door readily between open and closed positions, mechanism is provided whereby the door is raised above the track and supported upon rolling means. This mechanism, commonly referred to as lift door elevating mechanism, embodies roller assemblies secured to the lower margin of the door adjacent the corners thereof. These assemblies as illustrated are identical in structure and each embodies a roller retainer 26 which carries a pin or axle 27 upon which a roller 28 is mounted. Aligned trunnions 29 and 30 project from each of the roller retainers 26 and are arranged in offset relationship to the pin or axle 27. The trunnion 29 is journaled in the vertical flange 21 of the bottom reinforcing angle 20 and the trunnion 30 is journaled in a 35

housing member 31 rigidly fastened to the door as by means of a plurality of rivets 32. The housing member 31 serves to enclose a roller assembly and by reason of the hook shaped extensions 33 formed on the roller housing and disposed in overlapping relationship with the track 23 functions as guide and retaining means for the door. Simultaneous movement of the roller retainers is secured by means of a connecting bar 34 disposed within the lowermost horizontal corrugation. The bar 34 is connected to projections 35 provided on the roller retainers by means of lugs extending from these projections into openings formed in the ends of the connecting bar.

15 The lift mechanism embodies an actuating lever 36 which in the form of the mechanism illustrated is mounted directly upon the trunnion 39. For this purpose the trunnion 39 extends beyond its bearing in the housing member and is provided 20 with flat faces 37 and 38. Securement of the lever upon the trunnion is obtained by means of a substantially Z-shaped member 39 fastened upon the rear of the lever as by means of a rivet 40, this member cooperating with an arcuate flange 25 41 formed on the housing member 31.

Heretofore the actuating levers of lift mechanisms have been subjected to a chattering or whipping action by reason of the constant movement of the railway cars and the doors thereon 30 occasioned by the normal travel of the cars over the rails. This chattering of the actuating levers set up progressive wear between the roller retainer trunnions and their bearings and between the actuating levers and the trunnions upon which 35 they are mounted. As this wear progressed, the actuating levers became loose upon the trunnions which in turn induced greater chattering and greater wear. This looseness, moreover, caused the actuating levers to depart from their initial 40 position and as they normally approached the track affected the amount of lift obtainable.

To the end that chattering of the levers may be substantially obviated the roller retainers are provided with flanges 42 projecting from the lower portion of the retainers. The door 10 is provided with rubber blocks 43, preferably cylindrical in shape. These blocks are supported upon horizontal flange 22 of the bottom reinforcing angle 20 and are maintained in position by means 50 of studs 44 extending inwardly from the housing members 31.

With reference to Figure 1 of the drawings wherein the door is illustrated in its lowered position, it will be apparent that the instant invention in the embodiment considered effectively prevents chattering of the actuating lever 36. By reason of the fact that the roller 28 engages the track 23, it is clear that swinging movement of the lever in a clockwise direction 45 cannot occur. Similarly, by reason of the engagement between the flanges 42 provided on the roller retainers 26 and the rubber blocks 43 which occurs in the lowering movement of the door so as to compress the rubber blocks, it will be apparent 55 that swinging movement of the lever in a counter-clockwise direction is precluded. Thus, chattering or whipping of the actuating lever is eliminated and the adverse effects heretofore resulting from such chattering are avoided.

70 With reference to Figure 3 of the drawings, it will be seen that there is no interference with normal lifting operation of the mechanism.

A further embodiment of the invention is illustrated in Figures 6 to 9, inclusive. In this embodiment the lift mechanism applied to the door 10

includes housing members 45—45 within which are disposed roller assemblies. Each of these embodies an eccentric roller designated in its entirety by the reference numeral 46. The eccentric roller comprises briefly a rim 47 and a core 48. A splined pin 49 extends eccentrically into the core 48 and is received within correspondingly splined journals 50 and 51 disposed respectively in aligned bearings formed in the housing member. Splined arms 52 are mounted 10 upon the pins 49 and are provided with lugs 53 which extend into openings formed in the ends of a connecting bar 54 to insure simultaneous lifting operation of the roller assemblies. An inwardly splined actuating lever 55 is mounted 15 upon one of the splined pins 49 and is guided and retained by means of an arcuate flange 56 formed on the housing member. The flange 56 cooperates for the purpose indicated with a substantially Z-shaped clip 57 carried on the rear side 20 of the lever. Except insofar as the eccentric rollers of the considered lift mechanism cooperate with means as hereinafter explained to prevent chattering of the actuating lever, such mechanism per se forms no part of the instant invention but 25 will constitute the subject matter of a separate application.

Each of the housing members 45 is provided with opposed retaining flanges 58 and 59 between which there is confined a rubber block 60. As 30 clearly appears from Figure 7 of the drawings, the rubber block 60 lies in the plane of the eccentric roller 46 and when the door is in lowered position the rubber block 60 is engaged and compressed by the rim 47 of the eccentric roller. By the described construction chattering or whipping of the actuating lever 55 is prevented. It is apparent that the lever 55 by reason of the engagement of the eccentric roller 46 with the track cannot move in clockwise direction as viewed in 40 Figure 7. Similarly, by reason of the engagement between the rubber block 60 and the eccentric roller upward movement of the roller about the pin 49 is prohibited and consequently movement 45 of the lever in a counter-clockwise direction is precluded. It appears, moreover, as illustrated in Figure 8 of the drawings, that the rubber block offers no interference to the normal lifting operation of the lift mechanism.

It will be apparent that numerous changes 50 and modifications in the details of the invention will be clear to those skilled in the art. It is intended, therefore, that all such modifications and changes be comprehended within this invention, which is to be limited only by the scope of 55 the claims appended hereto.

I claim:

1. In a railway house car having a sliding door and a track associated therewith and frictionally supporting said door in lowered position, elevating mechanism for said door, said mechanism comprising an actuating lever and rolling means adapted to engage said track, and a resilient member on said door, said member being compressed by said mechanism in the lowering movement of said door, said rolling means being engaged with said track when said resilient member is compressed, said resilient member being released from the pressure of said lift mechanism upon operation of said lever to raise said door.
2. Lift mechanism for a sliding lift door comprising a roller, a retainer for said roller, said retainer being eccentrically mounted on said door, a flange projecting from said retainer, an actuating lever operatively associated with said

retainer and a resilient member carried by said door, said member being compressed by said flange in the lowered position of said door.

3. Lift mechanism for a sliding lift door comprising an eccentric roller, an actuating lever

5 operatively associated with said roller, a housing member for said roller secured to said door, and resilient means carried by said housing member engaging said roller in the lowered position of 10 said door.

4. Lift mechanism for a sliding lift door comprising an eccentric roller, an actuating lever operatively associated with said roller, a housing member for said roller secured to said door, 15 retaining flanges on said housing member and a resilient member carried by said flanges, said resilient member engaging said roller in the lowered position of said door.

5. In a railway house car the combination with 20 a sliding door, a track for frictionally supporting said door in lowered position and lift mechanism for said door embodying rollers adapted to engage said track, retainers for said rollers provided with trunnions disposed in offset relationship to the axis of said rollers and journalled in 25 said door and an actuating lever mounted upon one of said trunnions, of resilient means carried by said door, at least one of said retainers engaging said resilient means during lowering movement of said door and compressing said means, said rollers being in engagement with said track when said resilient means is compressed.

6. In a railway house car the combination with a sliding door, a track for frictionally supporting said door in lowered position and lift mechanism for said door embodying rollers adapted to engage said track, means journalled in said door 5 eccentrically mounting said rollers, a bar connecting said means for simultaneous rotation and a lever secured to one of said means for imparting rotation thereto, of resilient means carried by said door, said roller mounting means being 10 rotated by lowering movement of said door to effect compression of said resilient means, said rollers being engaged with said track when said resilient means is compressed, said lever being operable to rotate said roller mounting means 15 to lift said door and relieve said resilient means of pressure.

7. In a railway house car the combination with a sliding door, a track for frictionally supporting said door in lowered position and lift mechanism for said door embodying rollers adapted to engage said track, retainers for said rollers provided with trunnions disposed in offset relationship to the axis of said rollers and journalled in 20 said door and an actuating lever mounted upon one of said trunnions, of resilient means carried by said door, at least one of said retainers being provided with a projecting flange, said flange engaging and compressing said resilient means during the lowering movement of said 25 door, said rollers being in engagement with said track when said resilient means is compressed.

FRANK DITCHFIELD.
